STRIKING HAMMER FOR FIREARMS

Antoine Gazda, Providence, R. I.

Application April 4, 1944, Serial No. 529,460

5 Claims. (Cl. 42—3)

The present invention relates to a novel and improved construction of striking hammer for firearms. While the invention is broadly applicable to semi-automatic as well as automatic types of firearms, it is particularly useful in the so-called "blow-back" type of automatic gun, i. e. the type wherein the rearward stroke of the breech block is effected with the aid of the recoil impulse derived from the gun gases.

Guns of the afore-indicated type are fired at a very high firing rate so that it is not unusual for the breech block and associated parts to describe, for example, as many as 1000 or more strokes per minute. It is manifest that this places a high strain on the parts which, however, must be of a character to withstand such strain if dangerous break-downs of the guns are to be avoided.

The present invention, the primary object of which is to solve the problem of avoiding such break-downs, does so by providing a relationship of parts, of which the striking hammer and its construction according to the present invention are of the essence, which is adapted successfully to endure the above-described high operative strain.

Briefly stated, the primary object of the invention is realized with the aid of a striking hammer construction which is modified to endow it with such resilience as enable it to withstand and counteract the repeated shocks to which it is subject in operation. Particulars of the modifications will appear from the detailed description hereinafter set forth.

Other objects of the invention will in part be obvious and in part pointed out in the said description, in which connection reference will be made to the accompanying drawing.

Accordingly, the present invention resides in the several elements and features of construction, and the correlation of these elements and features, all as described herein and as recited in the appended claims.

The accompanying drawing discloses presently-preferred embodiments of the invention. Of the several figures,

Fig. 1 is a somewhat diagrammatic view, partly in section and partly in elevation, of the relationship of parts according to the invention and of adjacent gun parts, showing one position of the striking arrangement;

Fig. 2 is a view similar to that of Fig. 1 and showing a second position of the striking arrangement;

Fig. 3 is still another view similar to that of Fig. 1 and showing still another position of the striking arrangement;

Fig. 4 is a perspective view of one form of striking hammer according to the invention;

Fig. 5 is a fragmentary view of a second form of striking hammer according to the invention; and

Fig. 6 is a fragmentary view of a third form of striking hammer according to the invention.

On the said figures of drawing, reference character 10 designates the barrel of the gun and 11 designates the breech tube in which the breech block 12 and associated parts slide backward and forward. Except as otherwise indicated, block 12 may be essentially conventional in character.

These associated parts comprise a striking hammer 13 arranged as shown in a recess 14 in the block 12, the hammer being journaled on pivot 15 provided for this purpose on block 12. Noses 16, 16' of the hammer project slightly beyond the said block, as shown.

Head 17 of the striking hammer is received in slot 18 provided in the extension 19 of firing pin 20 which is mounted for reciprocal movement in correspondingly-shaped bore 21 provided in the block. Flanged bushing 22 provided in bore 21 provides, at its inner end an abutment defining the outward limit of movement of the pin 20. The bushing flange constitutes a cartridge pushing element.

In the illustrated type of automatic gun, the sequence of operations during firing is essentially as follows:

35 The breech block 12 being in cocked position, and a cartridge 23 from the cartridge magazine (not shown) having taken its place in front of the breech block upon release of the trigger, the block together with associated parts starts moving forward under the influence of the conventional means (not shown) provided for this purpose. Fig. 1 shows the relationship of parts with the breech block in forward stroke, the cartridge 23 being pushed into the cartridge chamber.

40 During this forward stroke, the striking hammer 13 approaches the striker plate 24 which extends, as shown, across the bottom of tube 11 into the path of projecting nose 16, noses 16' in this position of the hammer being elevated to extent enabling them to clear the plate.

45 Continued forward movement of the breech block results (Fig. 2) in interengagement of nose 16 and striker plate 24 causing the hammer 13 to rotate about its pivot pin 15 to produce relative movement between the firing pin and breech

block, with the result that pre-percussion takes place and the cartridge is ignited.

After ignition has occurred, explosion takes place and the resultant gas pressure impels the projectile 25 through the barrel 10 (Fig. 3), at the same time braking the forward motion of the breech block 12. Thereby the gas pressure loses about half of its recoil impulse. This reduced remaining impulse pushes the breech block backwards, at the same time pushing out and then ejecting the cartridge case.

Fig. 3 shows the breech block at its foremost reversal point. During the rearward stroke, both noses 16' of the hammer 13 strike against the striker plate 24, raising these noses and causing the striking hammer and firing pin to revert to their starting position whereupon, the trigger continuing released, the above described firing action is repeated.

Notwithstanding the fact that the striking hammer 13 is preferably made of heat-treated high alloy steel, precision ground to shape, the continuous and rapid hammering action which takes place between the hammer noses and the striking plate 24, during firing, has a tendency to give rise to fracture lines generally emanating from the point x (Fig. 2).

It has been found that by imparting some elasticity to the hammer noses 16 and 16', the tendency to the formation of the said fracture lines appears to be essentially eliminated.

As shown in Figs. 4, 5 and 6, the striking hammer has a fork-shaped forward end, providing a pair of spaced noses 16', a single depending nose 16 being provided on the other end.

According to the invention, the desired elasticity is imparted to the hammer noses by providing each of them with a slot 26 extending transversely and substantially centrally thereof, as shown, from the lower surface back somewhat more than half, preferably approximately two-thirds, of the length of the nose. The depth of the slot is not absolute and some latitude in either direction is permissible. The slotting may be effected in any desired manner, as for example by grinding.

Each slot 26 subdivides its nose into nibs which possess the considerable relative elasticity which enables the object of the invention to be essentially realized.

In order to avoid the generation of random fracture lines from the bottom of the slots, each slot 26 is preferably provided, according to the embodiment of Fig. 4, with an enlarged rounded bore 27 at the bottom thereof.

The degree of resiliency of the nibs may be controlled by controlling the configuration of the bottom of the slots 26. Thus, according to Fig. 5, instead of providing an enlarged bore 27, the bottom of the bore is rounded along a generatrix 28 having a radius R equal to $\frac{1}{2}W$ (W being the width of the slot).

According to Fig. 6, the generatrix 29 constituting the bottom of the slot has an even smaller radius, the ends thereof being rectilinearly connected with the surfaces of the slot 26.

Having thus disclosed the invention, what is claimed is:

1. In a firearm of the class described, a breech tube, a striker plate projecting inwardly of the tube, a breech block reciprocable in the tube, a firing pin longitudinally slidable in the breech block, a hammer lever pivoted in the breech block and operably connected with the firing pin, and spaced transversely slotted noses on the hammer lever in positions to engage the striker plate during reciprocation of the breech block.

2. In a firearm of the class described, a breech tube, a striker plate projecting inwardly of the tube, a breech block reciprocable in the tube, a firing pin longitudinally slidable in the breech block, a hammer lever pivoted in the breech block, said lever having a portion engaging the firing pin, and spaced transversely slotted noses on the opposite end of the lever, said noses being positioned to engage the striker plate during reciprocation of the breech block.

3. In a firearm of the class described, a breech tube, a striker plate projecting inwardly of the tube, a breech block reciprocable in the tube, a firing pin longitudinally slidable in the breech block, a hammer lever pivoted in the breech block and operably connected with the firing pin, the forward portion of the lever being bifurcated and forming spaced dependent noses, the rear portion of the lever having a single dependent nose, all of said noses being transversely slotted in a vertical direction and engaging said striker plate during reciprocation of the breech block.

4. In a firearm of the class described, a breech tube, a striker plate projecting inwardly of the tube, a breech block reciprocable in the tube, a firing pin longitudinally slidable in the breech block, a hammer lever pivoted in the breech block and operably connected with the firing pin, said lever having front and rear dependent noses in positions to engage opposite sides of the striker plate during reciprocation of the breech block, each of said noses being divided transversely and vertically for a major part of the height thereof.

5. In a firearm of the class described, a breech tube, a striker plate projecting inwardly of the tube, a breech block reciprocable in the tube, a firing pin longitudinally slidable in the breech block, a hammer lever pivoted in the breech block and operably connected with the firing pin, said lever having front and rear dependent noses in positions to engage opposite sides of the striker plate during reciprocation of the breech block, each of said noses having a transverse slot in a vertical plane, said slots being transversely enlarged at their inner ends.
